Filed Feb. 25, 1965, Ser. No. 441,951
12 Claims. (Cl. 118—246)

ABSTRACT OF THE DISCLOSURE

The disclosure relates to a box tab gluer having a reservoir kept full of glue by a glue source which imposes hydrostatic pressure on the glue which tends to force glue out of the reservoir through a gap between the reservoir wall and a glue applying roller. The roller is powered to turn its periphery toward the gap, thus imposing back pressure on the glue in the gap and precluding outward flow thereof.

This application is a continuation-in-part of our co-pending application Ser. No. 263,223, filed Mar. 6, 1963, now abandoned.

This invention relates to a box tab gluer.

The embodiments of the invention shown for exemplification herein constitute various forms of attachment for a box making machine. In gluers typically embodying the invention, there is a source of glue under pressure and a glue reservoir having a glue applying roller exposed thereto. A box tab is passed over the roller which picks up glue from the reservoir and deposits it on the tab. There is a gap between the roller and the wall of the reservoir. Accordingly, the gap is subject to the pressure of the glue source which tends to cause the glue to flow through the gap.

According to the present invention, however, the glue roller is powered and its periphery is rotated toward the gap to develop sufficient friction with the glue in the gap to impose back pressure on the glue in the gap and counteract the pressure of the glue source, thus to preclude glue flow through the gap. As long as the roller periphery continues to rotate toward the gap, glue leakage will not occur.

The present invention eliminates the need for glue-tight seals around the roller.

In the gluer of the present invention, the glue reservoir and the glue applying roller are interposed between the inside and outside tabs of the box blank which are normally folded in overlapping relation. Accordingly, these parts function to spread and support the tabs in spaced apart relation, as glue is applied to one of the tabs.

In some embodiments of the invention, the roller and reservoir are tapered toward the folded connection or joint between the outside tab and the box blank, thus to better conform to the shape of the box blank in its spread apart relationship.

Other objects, features and advantages of the invention will appear from the following disclosure in which:

FIG. 1 is a vertical section taken through one form of gluer embodying the invention, this section being taken along the line 1—1 of FIG. 2.

FIG. 2 is a vertical section transverse to that of FIG. 1, and taken along the line 2—2 of FIG. 3.

FIG. 3 is a plan view of the gluer aforesaid.

FIG. 4 is an enlarged fragmentary cross section showing details of the glue-applying roller in association with the glue reservoir.

FIG. 4a is a fragmentary cross section taken along the line 4a—4a of FIG. 3.

FIG. 4b is a fragmentary cross section taken along the line 4b—4b of FIG. 3.

FIG. 5 is a vertical section taken through another form

2

of the gluer embodying the invention, this section being along the line 5—5 of FIG. 6.

FIG. 6 is a vertical cross section transverse to that of FIG. 5, and taken along the line 6—6 of FIG. 7.

FIG. 7 is a plan view of the gluer embodiment shown in FIGS. 5 and 6.

FIG. 8 is an enlarged fragmentary cross section of the roller and reservoir of the embodiment shown in FIGS. 5 through 7.

FIG. 9 is a fragmentary cross section taken along the line 9—9 of FIG. 6.

FIG. 10 is a vertical section taken through a modified form of gluer embodying the invention in which the reservoir and roller are tapered toward the folded connection of the outside tab to the box blank and in which the roller applies glue to the inside tab.

FIG. 11 is a vertical section taken through another form of gluer embodying the invention in which the reservoir and roller are tapered toward the folded connection of the outside tab to the box blank and in which the glue is applied to the undersurface of the outside tab.

FIG. 12 is a perspective view of the tapered roller incorporated in the embodiments of FIGS. 10 and 11.

Like parts in the several views are given the same reference characters.

Although the disclosure hereof is detailed and exact to enable those skilled in the art to practice the invention, the physical embodiments herein disclosed merely exemplify the invention which may be embodied in other specific structure. The scope of the invention is defined in the claims appended hereto.

The gluer shown in FIGS. 1—4 may conveniently be attached by bracket 11 to beam 12 of a conventional box making machine. The embodiment shown in these figures is adapted to lay strips or beads of glue on the "inside" tab 13 of the corrugated cardboard box blank indicated generally by reference character 14. The box blank 14 has an "outside" tab 15, which, after inside tab 13 has been glued, will be pressed thereagainst by the traveling belts 16, 17, to form the manufacturer's joint of the box blank.

Bracket 11 suspends the gluer 18 which consists of a glue reservoir or sump 19, the otherwise open end of which is almost completely closed by glue applying roller 20. Roller 20 is desirably provided with circumferential grooves 21 into which glue 22 from the reservoir 19 will be deposited as the roller turns in the direction of arrow 38. Reservoir 19 has a bottom wall 25 over the inside surface of which doctor blade 26 is slidably mounted. The blade 26 is adjustable towards and away from the periphery of roller 20 by turning adjusting screw 27 which is threadedly engaged with the fixed nut 28. Ordinarily, the doctor blade 26 will be adjusted for light scraping contact with the periphery of the roller 20, thus to limit transfer of glue to the roller to that which adheres to the grooves 21 thereof. The doctor blade 26 closes the space between the reservoir and the peripheral surface of the roller 20 along a first line which is spaced arcuately around the peripheral surface of the roller from a second line along which cover plate 29 is spaced from the peripheral surface of the roller.

Reservoir 19 also has a top wall or cover plate 29 which overhangs roller 20. Duct 30 leads from reservoir 19 to a glue supply means such as storage tank 31. The glue 22 in tank 31 is at a level considerably higher than the reservoir 19, thus to supply glue thereto under hydrostatic pressure. If desired, the tank 31 could be replaced by a hose leading to a remote source of glue under pressure sufficient to constantly replenish glue in reservoir 19.

Cover plate 29 is spaced from the peripheral surface of roller 20 along a second line which is spaced arcuately around the peripheral surface of the roller from the first line aforesaid. In accordance with the present invention, no attempt is made to seal the space between reservoir cover plate 29 and the periphery of the glue roller 20. On the contrary, a space or gap 34 is left therebetween, as is best shown in FIG. 4. Under these circumstances, the hydrostatic pressure of the glue in tank 31 would ordinarily tend to force the glue to leak through the gap 34.

In accordance with the present invention, however, roller 20 is mounted on a shaft 35 which may be power driven in the direction of arrow 38, for example, by belt 36 from motor 37 or the like. Accordingly, the periphery of the roller 20 moves toward and into the gap 34 and against the direction in which the glue would otherwise leak therethrough. The friction between the roller periphery and the glue creates a back pressure in the gap 34 which counteracts or balances the hydrostatic pressure of the glue in the tank 19 and precludes glue flow or leakage through the gap 34. The back pressure will depend somewhat upon the specific gravity of the glue, which is ordinarily semi-viscous. In practice, sufficient back pressure is developed to preclude leakage of even very thin glue formulations.

The box blank 14 is fed through the gluer 18, as shown in FIGS. 1 and 2. The inside tab 13 and outside tab 15 which are in overlapping relation in the box blank 14 are spread apart by passing on opposite sides (top and bottom) of the reservoir 19. Accordingly, the reservoir 19 comprises means to spread and support the tabs in spaced apart relation while glue is applied to the surface of one of the tabs, in this case tab 13. The "inside" tab 13 of the blank 14 passes over the apron 39 and is subject to the light upward bias of leaf spring 41 against the undersurface of the glue applying roller 20. Apron 39 comprises guide means to guide the tab 13 against roller 20. Roller 20 is driven in the direction of arrow 38 and will deposit beads or ribbons 40 of glue into the upper exposed surface of the tab 13. As aforesaid, no glue will leak through the gap 34 by reason of the back pressure developed at this point by rotation of roller 20 in the direction of arrow 28.

After the tab 13 has passed beyond the gluer in the direction of feed as shown by arrow 43, the outer tab 15 will be brought into pressure engagement with tab 13 by reason of the traveling belts 16, 17, thus to glue the tabs together and form the manufacturer's joint in the box blank.

FIGS. 5-8 show a modified embodiment of the invention in which the beads or ribbons 40 of glue are applied to the outside tab 15 of the blank 14. Like parts are given the same reference characters as in the embodiment of FIGS. 1-4.

The only substantial difference as between the two embodiments is that the glue applying roller 20 has its upper surface exposed to the undersurface of the outer tab 15 and inside tab 13 does not receive any glue treatment until brought into pressure engagement with tab 15 by reason of the action of the traveling belts 16, 17.

The reservoir 44 is of slightly different construction, in that its bottom 45 is closed. The top wall or cover plate 46 of the reservoir 44 is adjustable on the set screws 47 to function as a doctor blade with respect to the roller 20. Roller 20 in this instance is rotated in the opposite direction to which it was rotated in the embodiment of FIGS. 1-4. Roller shaft 35 is driven by motor 37 through belt 36 in the direction of arrow 49. In this instance, the gap 48 through which the hydrostatic pressure of the glue 22 would ordinarily cause leakage is between the periphery of the roller 20 and the bottom wall 45 of the reservoir 44. No leakage occurs between the doctor blade and the roller 20. Because of the back pressure produced in the gap 48 by reason of rotation of the roller toward the gap, no leakage occurs through the gap.

A guide means such as wheel 51 is provided to press the outside tab 15 downwardly against the roller 20 and insure proper application of the beads or ribbons of glue 40 to the tab 15.

In both of the embodiments above described, the roller is rotated toward a gap which need not be provided with conventional seals because of the back pressure produced therein as aforesaid. Accordingly, the device will not leak, even when there is no box blank in the machine, as long as the roller 20 is rotated in the proper direction to develop back pressure balancing the hydrostatic pressure of the glue source.

FIG. 4a shows an optional feature of all embodiments of the invention. Grooves 60 are formed in the side walls of the reservoir 19 at each end of the roller 20. Grooves 60 have arcuate portions just within the outer periphery of the roller 20 and have tangential or tail portions 61 which lead into the reservoir 19. Accordingly, as the roller 20 turns in the direction of arrow 38, any glue which tends to leak past the ends of the roller is caught in the grooves 60 and is returned to the reservoir 19 under pressure of the rotating wheel.

Another optional feature of all embodiments of the invention is shown in FIG. 4b. A spiral groove 62 is formed in each end of the roller 20. As the roller turns in the direction of arrow 38 any glue trapped at the ends of the roller is carried away from shaft 35 and outwardly to the periphery of the roller. This keeps the glue out of the bearings for shaft 35. This feature also permits some slight end play in the roller without danger of leakage. In a practical embodiment of the invention the end play thus allowed exceeds .002 inch.

Another optional but desirable feature of all embodiments of the invention is shown in FIG. 9, which shows details of the sleeve bearings 63, 64 in walls 65, 66 of reservoir 44. A grease fitting 67 is provided for bearing 63 and grease fitting 68 is provided for bearing 64. Grease is forced under pressure into the bearings to exclude any glue which tends to work into the bearings and to act as a barrier to the entry of glue. After the gluer is used and washed up, charges of grease are forced through each fitting 67, 68. Enough grease is used to fill the space between the end of the roller 20 and the side walls of the reservoir. This prevents the roller from sticking to the walls, when not in operation.

In the embodiments of FIGS. 1 through 9, the roller 20 is cylindrical and the reservoirs 19, 44 have spaced parallel tops and bottoms. FIGS. 10 and 11 show modified embodiments in which the roller 80 is conical in shape and in which the respective reservoirs 81, 82 are tapered outwardly from the support standard 11 toward the joints 83 on which the sides 84 of the box blank are foldably connected to side 85 thereof. Accordingly, the tapered roller 80 and reservoirs 81, 82 have sloped upper surfaces which better conform to the slope of the box blank panels 15, 84 which pass over the top of the reservoir. This is particularly advantageous where the box blank is narrow, as shown in FIGS. 10 and 11, as compared to a box blank which is wide, as shown in FIGS. 1 and 5. In narrow box blanks the fold line 83 is closer to the gluer. The construction shown in FIGS. 10 and 11 will produce less bending stresses on the box blank than the embodiment shown in FIGS. 1 and 5.

In other respects, the devices shown in FIGS. 10 and 11 are similar in construction to those previously described. In the embodiment of FIG. 10, the roller 80 applies beads or ribbons of glue to the upper surface of inside tab 13. For this purpose, the tab 13 is guided by the apron 39 and the pressure of the leaf spring 41 against the undersurface of the roller 80, in much the same manner as is shown in FIGS. 4 and 4a, except that the roller 80 is tapered as aforesaid.

In FIG. 11 the relationship between the roller 80 and the reservoir 82 is similar to that shown in FIG. 8 (except for the taper of the roller and the reservoir). A guide

wheel 51 presses the outside tab 15 against the upper surface of the roller 80. The guide roller 51 is provided with an inclined bearing tube 86 for its shaft 87.

Respective rollers 80, shown in FIGS. 10 and 11, have drive shafts 88 which are inclined as shown in these figures to accommodate for the taper of the rollers 80. The ends of the shafts have belt pulleys 89 for the drive belts 90.

As in the previously described embodiments, each roller 80 is desirably provided with circumferential grooves 90 which meter the amount of glue deposited in bands or ribbons, as shown at 40 in FIGS. 4 and 8. Accordingly, the doctor blade may scrape against the ungrooved surface of the roller leaving only the glue in the grooves 90 to be applied to the tab surface. The rollers 80 may also be provided with end spiral grooves, as shown in FIG. 4b, and the reservoir walls may be provided with grooves such as 60, 61, as shown in FIG. 4a.

In all embodiments of the invention, the gluer functions to separate and maintain the tabs 13, 15 in spaced relationship as the glue is applied by the roller to that surface of one or the other of the tabs which will face a corresponding surface of the other tab when the tabs are brought together under pressure of the belts 16, 17.

What is claimed is:

1. A box tab gluer for a box blank having inside and outside tabs folded in said blank in overlapping relation, said gluer comprising:

a glue applying roller having a peripheral surface, a glue reservoir to which the roller is exposed to pick up glue therefrom,

said reservoir comprising means to spread and support said tabs in spaced apart relation as glue is applied to one of said tabs,

guide means for guiding one of said box tabs against said peripheral surface of said roller,

said reservoir having:

a doctor blade substantially closing the space between said reservoir and the peripheral surface along a first line at one side of the roller,

and a wall portion spaced from the peripheral surface along a second line at another side of the roller to leave a gap between the wall portion and the peripheral surface of the roller along said second line,

said first and second lines being spaced arcuately around the periphery of said roller,

means to fill said reservoir with glue and including a source of hydrostatic pressure for the glue in the reservoir to tend to cause said glue to flow through said gap,

and power means to rotate the periphery of said roller toward said gap to develop sufficient back pressure in the glue in said gap to counteract said hydrostatic pressure and preclude glue flow through said gap.

2. The gluer of claim 1 in which said source of hydrostatic pressure comprises a glue tank at a higher elevation than the glue reservoir and communicating therewith.

3. The gluer of claim 1 in which said guide means guides the box tab beneath the roller, said doctor blade being disposed along the bottom of the reservoir, said power means rotating the periphery of the roller away from the doctor blade, said guide means including means for urging the tab upwardly against the roller.

4. The gluer of claim 1 in which said guide means guides the box tab above the roller, said doctor blade being disposed along the top of the roller, said power means rotating the periphery of the roller away from the doctor blade, said guide means including means for urging the tab downwardly against the roller.

5. The gluer of claim 1 in which an end of the glue-applying roller is provided with a spiral groove to carry glue toward the roller periphery as the roller turns.

6. The gluer of claim 1 in which said reservoir has side walls between which the roller is disposed, at least one of said walls having a groove leading in the direction of roll rotation from within the periphery of the roller to said reservoir.

7. The gluer of claim 1 in which said reservoir has side walls between which said roller is disposed, said roller having a shaft and bearings for said shaft in said walls, and grease fittings for said bearings by which grease is charged into said bearings.

8. The gluer of claim 1 in which the peripheral surface of the roller has circumferential grooves in which glue is carried past the doctor blade.

9. The gluer of claim 1 in which the roller and reservoir are tapered toward the fold of said outside tab with the box blank.

10. A box tab gluer for a box blank having inside and outside tabs folded in said blank in overlapping relation, said gluer comprising:

means to spread and support said tabs in spaced apart relation as glue is applied to one of said tabs,

25 said means comprising a glue applying roller between said tabs and having a peripheral surface and a glue reservoir to which the peripheral surface of the roller is exposed to pick up glue therefrom, guide means for guiding one of said box tabs against the peripheral surface of the roller, said reservoir having:

a doctor blade substantially closing the space between said reservoir and the peripheral surface along a first line at one side of the roller, and a wall portion spaced from the peripheral surface along a second line at another side of the roller to leave a gap between the wall portion and the peripheral surface of the roller along said second line,

30 said first and second lines being spaced arcuately around the periphery of said roller,

means to fill said reservoir with glue and including a source of hydrostatic pressure for the glue in the reservoir to tend to cause said glue to flow through said gap,

35 and power means to rotate the periphery of said roller toward said gap to develop sufficient back pressure in the glue in said gap to counteract said hydrostatic pressure and preclude glue flow through said gap.

40 11. The gluer of claim 10 in which the roller and reservoir are tapered toward the fold of said outside tab with the box blank.

12. The gluer of claim 11 in which the roller has circumferential grooves in which glue is carried past the doctor blade.
